UNITED STATES PATENT OFFICE.

WILLIAM M. BELT, OF BLOOMINGTON, ILLINOIS, ASSIGNOR TO ILLINOIS SPECIALTY MANUFACTURING COMPANY, OF BLOOMINGTON, ILLINOIS, A CORPORATION OF ILLINOIS.

DESIGN FOR A HEATER.

57,101. Specification for Design. Patented Feb. 22, 1921.

Application filed February 16, 1920. Serial No. 359,188. Term of patent 14 years.

To all whom it may concern:

Be it known that I, WILLIAM M. BELT, a citizen of the United States, residing at Bloomington, in the county of McLean and State of Illinois, have invented a new, original, and ornamental Design for a Heater, and of which the following is a specification, reference being made to the accompany drawing, forming a part thereof, in which—

Figure 1 is a perspective view showing the front, top and side of my heater.

Fig. 2 is a perspective view showing the rear, bottom and side of my heater.

I claim:

The ornamental design for a heater as shown.

WILLIAM M. BELT.
